COAL CUTTING MACHINE

Hubert D. Fanning and Loyd V. Fanning,
Bokoshe, Okla.

Application April 12, 1939, Serial No. 267,502

3 Claims. (Cl. 262—29)

This invention relates to a coal cutting machine, the general object of the invention being to provide a machine which is mainly designed for small mine owners or operators as the machine is so constructed that it can be manufactured to sell at low cost, is easy of operation and requires but little power to operate it.

Another object of the invention is to provide an endless member having cutting teeth thereon, a support for the same, a frame structure adapted to be erected in the mine and which carries the supporting member, with means for feeding the supporting member across the frame structure as the endless member is being actuated.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a top plan view of the invention.

Figure 2 is a front view thereof.

Figure 3 is a section on the line 3—3 of Figure 1.

Figure 4 is a section on the line 4—4 of Figure 1.

Figure 5 is a section on the line 5—5 of Figure 2.

Figure 6 is a section on the line 6—6 of Figure 2.

Figure 7 is a section on the line 7—7 of Figure 2.

Figure 8 is a section on the line 8—8 of Figure 2.

Figure 9 is a section on the line 9—9 of Figure 1.

Figure 10 is a section on the line 10—10 of Figure 1.

Figure 11 is a fragmentary plan view with parts omitted showing how the cutting teeth of the endless chain engage the toothed wheel.

Figure 12 is an edge view of one of the toothed wheels.

Figure 13 is a view of one of the cutting teeth.

In these drawings the numeral 1 indicates an elongated light platform to the upper face of which is secured a top member 2 which has rounded ends and which terminates an appreciable distance from the front end of the platform.

Two parts are connected together by the bolts 3 and the two parts 1 and 2 are provided with projecting parts 4 which form a channel at the sides and ends of the member. Portions of the two members 1 and 2 are cut away to provide substantially circular openings 5 in which are located the toothed wheels 6, each of which includes a pair of toothed disks 7 connected together in spaced relation by a cog 8. One of these double pair of wheels is located at each end of the member 2 and one or more intermediate the ends thereof and endless chains 9 pass over these wheel parts, these chains carrying the curved cutting teeth 10. These parts are so arranged that the bases of the teeth will enter the notches of the toothed disks 7 so that the endless chains are caused to move by the wheel assemblies. A shaft 11 is journaled between the parts 1 and 2 and has worms 12 thereon meshing with the cog wheels or worm members 8 so that when the shaft 11 is rotated the wheel assemblies will be rotated and thus movement will be imparted to the two endless chains. The shaft 11 extends to a point adjacent the front end of the platform 1 where it may be connected to a motor, crank or any other suitable means for rotating it and a guard 13 extends upwardly from the platform 1 adjacent the inner or front end of the part 2 as shown in Figures 1 and 3. An upright frame is provided for supporting the platform 1 and the parts attached thereto and this frame includes the jacks 14, the bottom cross bar 15 and the top cross bar 16. A carriage 17 is suitably attached to the underside of the front portion of the platform 1 and carries the wheels 18 which engage grooves 19 in the sides of the cross bar 16 so that the platform and the parts carried thereby can be moved back and forth over the upper cross bar 6 of the supporting frame. Movement in one direction is imparted to the platform by the power means which drive the shaft 11 through means of a toothed wheel 20 engaging rack teeth 21 formed on the upper edge of the bar 16 and this wheel 20 can be connected with the shaft 11 or disconnected therefrom by shifting the gear 21 on shaft 11 through means of the lever 22. These parts are so constructed and arranged that the platform will be moved on the supporting frame at a speed which will conform to the cut being made in the coal surface by the cutting teeth.

The cross bar 16 can be adjusted vertically on the jacks 14 or placed at an angle thereon through means of a vertical row of holes 25 in each jack any one of which is adapted to receive

55 50 55

a bolt 26 passing through a hole at each end of the cross bar 16 and the cross member 15 can be adjustably connected to the lower end of the jacks 14 in any suitable manner. Preferably the 5 lower end of each jack is provided with the teeth 27 for engaging rough parts of the mine floor and the upper part of each jack is formed of a sliding part 28 having the teeth 29 at its upper end, this sliding part being connected with a 10 threaded shank 30 passing through a threaded hole in a gear 31 with which meshes a gear 32 having a stub shaft 33 connected therewith and extending through a hole in the hollow upper part of the jack so that a handle can be connected with the shaft 33 to raise and lower the 15 part 28 to engage and disengage the top of the jack with the ceiling of the mine.

Thus it will be seen that an operator after setting up the supporting frame can move the plat- 20 form 1 across the frame by manipulating the lever 22 to connect the shaft 11 with the ratchet wheel 20 and this rotation of the shaft 11 will drive the two cutting chains so that a cut is made in the wall of the mine. The teeth should be so 25 formed as to make a cut deep enough for the passage of the entire cutting member composed of the bars 1 and 2 and the parts enclosed thereby.

As before stated this invention is mainly de- 30 signed for use by operators of small mines where the large machines will be too expensive and require too much time.

It is thought from the foregoing description that the advantages and novel features of the invention will be readily apparent.

35 It is to be understood that changes may be made in the construction and in the combination and arrangement of the several parts provided that such changes fall within the scope of the appended claims.

40 Having described the invention, what is claimed as new is:

1. A coal cutting machine comprising an elongated member having a channel in its sides and ends, said member being composed of upper and 45 lower members connected together and having circular recesses therein, a wheel assembly rotat-

ably arranged in each recess and including upper and lower toothed disks and a worm wheel between the disks and connected therewith, endless chains passing over the toothed disks, teeth carried by the chain and having portions engaging the teeth of the disks, a shaft rotatably supported by the two members of the elongated member and worms carried by said shaft and engaging the worm wheel.

2. A coal cutting machine comprising an elongated member having a channel in its sides and ends, toothed wheels carried by the member, endless chains passing over the toothed wheels, cutting teeth carried by the chains, means for rotating the wheels to move the chains and 15 means for supporting the member, said means including an upright frame including a cross member having rack teeth thereon, a carriage connected with the elongated member and slidably connected with the cross member, a ratchet 20 wheel carried by the elongated member and engaging the rack teeth, and manually operated means for connecting the drive means of the toothed wheels with said ratchet wheel.

3. A coal cutting machine comprising a plat- 25 form, a top piece connected with the platform and of less length thereof, said platform and top piece having a channel formed at the edges and ends of the same, circular recesses formed in said platform and top piece, a wheel assembly 30 rotatably arranged in each recess including upper and lower disks and a worm wheel between the disks connected therewith, endless chains passing over the toothed wheels, cutting teeth carried by the chains, a shaft rotatably supported 35 between the platform and top member, worms on said shaft engaging the worm wheels, a pair of jacks, cross pieces adjustably connected therewith, one cross piece having a rack thereon, a carriage connected with the platform and engag- 40 ing said cross piece, a ratchet wheel on the platform engaging the rack teeth, manually operated means for connecting the shaft with the ratchet wheel.
